UNITED STATES PATENT OFFICE

ARTHUR C. KOOTZ, OF MILWAUKEE, WISCONSIN

MOP

Original application filed August 15, 1927, Serial No. 212,934. Divided and this application filed November 3, 1930. Serial No. 493,093.

The invention relates to mops and more particularly to polishing or dusting mops of the type wherein the mop material is removably secured to the mop head or frame so that it may be readily taken off for washing or renewal.

One object of the invention is to provide a mop supporting frame which extends through a channel or pocket in the mop body and the ends of which are secured to the pivot pin associated with the handle connector, one of said ends having a slidably releasable connection with said pivot pin which prevents the removal or the working off of the mop from the frame and which may be manipulated without the use of any tools when it is desired to take the mopping material from the frame. In this connection the present invention constitutes a further development of my prior application Ser. No. 212,934 filed August 15, 1927.

A further object of the invention is to provide a new and improved mop body which permits the reversing of the mop so that it may be used on either side and wherein the frame receiving portion comprises a piece of fabric formed into a tube and has the mop strands stitched thereto along its length in radially spaced rows.

30 The invention further consists in the several features hereinafter set forth and more particularly defined by claims at the conclusion hereof.

In the drawings, Fig. 1 is an elevation view of a mop embodying the invention, parts being broken away and parts being shown in section;

Fig. 2 is a vertical sectional view taken on the line 2—2 of Fig. 1;

Fig. 3 is a top plan view of a portion of the mop frame and handle showing certain modifications, parts being shown in section;

Fig. 4 is a side elevation view of the parts shown in Fig. 3 with a part shown in section;

Fig. 5 is a detail sectional view taken on the line 5—5 of Fig. 4.

In the drawings, the numeral 9 designates 50 the mop body, 10 the supporting frame, 11

the pivot member, 12 the handle connector, and 13 the handle.

The mop body may be of known construction such as shown in the aforementioned application Serial No. 212,934, but preferably is a new and improved construction shown in detail in Figs. 1 and 2 and includes a piece or strip of fabric whose longitudinally extending edges 14 are secured by lengthwise extending stitching 15 to form a tube 16 through which the wire 10 forming the frame may be inserted so as to mount said mop body on said frame. This mop body also includes radially spaced rows 17 of strands 18 of suitable fibrous mopping material, said strands being secured to fabric of said tube 16 by rows of stitching 19 preferably before the fabric is stitched into tubular form. Thus the strands projecting from the mop body present a mopping surface no matter which side of the frame is presented to the work.

The mop frame 10 is, as noted, preferably formed of wire and may take various shapes such as the elongated or generally oblong shape as shown in Fig. 1 with the mopping material thereon or any other desired shape. In any case the end portions 21 and 22 of the frame extend inwardly from its periphery from the rear end thereof.

As shown in Figs. 1 and 2, the end 21 of the frame is releasably mounted in a hole 23 formed in the end portion of the pivot member 11 and while the resiliency of the frame will hold said end in said hole in order to prevent any accidental withdrawal, the end portion of said end 21 may be threaded to receive a nut 24 which can be removed without tools and permits the withdrawal of this end of the frame from said member so that the mop material or mop body may be readily slipped off of said frame. The other end 22 of the frame is mounted in an aperture similar to the hole 23 and formed in the other end of said pivot member but is preferably fixed therein as by drive fitting, upsetting or pinning these parts together.

The handle connector 12 may be of any suitable construction to engage the pin 11 and provide a socket for the handle 13. As shown in Figs. 1 and 2 this handle connector

is formed of sheet metal to provide a split socket portion 25 securely clamped to the handle by the bolt 26 and nut 27 and provided at its forward end with pin engaging jaw portions 28 adjustably clamped to said pin by the bolt 29 provided with the clamping wing nut 30.

In the construction shown in Figs. 3 to 5 inclusive, the frame 31 which may be formed 10 in the shape shown by the dotted lines in Fig. 1 has an eyed end 32 through which the pivot bolt 33 passes, said bolt being in the form of an eyed member threaded to receive the clamping nut 34 and passing through 15 openings 35 in the flattened extensions 36 of a handle connector 37 whose socket portion 38 is similar to the socket portion 25 and similarly secured to the handle 13' by a clamping bolt 39. The eye 40 of the member 20 33 is adapted to releasably receive the end 41 of the frame 31 so that it may be readily withdrawn therefrom to remove the mop material mounted thereon. The end 41 of the frame 31 may be threaded to receive a nut 25 41' to hold this end against accidental removal. Metal washers 42 are disposed on the pin or pivot member 33 and to protect the furniture or other objects from contact with these metal parts, washers 43 of felt or other 30 suitable cushioning material are also mounted on said pin adjacent the extensions 36. The parts above described through which the pin passes are clamped together on the pin by the nut 34.

35 With all the above constructions it will be understood that the wire forming the frame is sufficiently resilient so that the separable end of the frame in each case may be sprung into the hole provided for it in the pivot bolt for the handle connector.

In the forms shown in Figs. 1 to 5, it will be noted that the mop frame may be turned relative to the handle so that either side of the mop body is presented to the work.

45 I desire it to be understood that this invention is not to be limited to any particular form or arrangement of parts except in so far as such limitations are specified in the claims or necessitated by the prior art.

50 What I claim as my invention is:

1. In a mop, the combination of a resilient mop-receiving frame having separable ends, a handle connector, a pivot pin on which said connector is pivotally mounted and having 55 an eye and a shank, one of said ends being mounted on said shank, the other of said ends slidably fitting in the eye of said pin and releasable therefrom, and a nut having threaded engagement with said shank for holding the same against removal from said eye and means securing said pin in operative position.

60 2. In a mop, the combination of a resilient mop-receiving frame having separable ends, a handle connector, a pivot pin on which 65

said handle connector is pivotally mounted having an eyed end and a threaded shank, one of the ends of said frame having an eye fitting said shank, the other of the ends of said frame having a slidably releasable connection with the eye of said pin, cushioning members on said pin between the ends of said frame and said connector, and a clamping nut mounted on said threaded shank.

70 In testimony whereof, I affix my signature. 75
ARTHUR C. KOOTZ.
